UNITED STATES PATENT OFFICE.

THOMAS SHEPHERD, OF OLDHAM, ENGLAND.

COMBINED LAMP AND SHADE HOLDER.

1,257,032.

Specification of Letters Patent. Patented Feb. 19, 1918.

Application filed December 4, 1916. Serial No. 135,030.

To all whom it may concern:

Be it known that I, THOMAS SHEPHERD, a subject of the King of Great Britain, and a resident of Oldham, England, have invented certain new and useful Improvements in Combined Lamp and Shade Holders, of which the following is a specification.

This invention has reference to an improved combined lamp and shade holder, and has for its object the provision of a new and improved device of this class particularly adapted for the accommodation of a hanging or depending light and its shade.

The invention consists in the provision of a socket shell comprising a suitably curved projection provided with holes or slots in which slide curved fingers bent at an angle at one end, and at the other fitted to operate with a circular spring ring. This socket shell and the curved fingers are adapted to form the gripping jaws which maintain the lamp shade in position. One end of the socket shell is formed to accommodate the lamp and its attendant parts and the other for attachment to any suitable fitting. This second end may be adapted to support the porcelain or other insulation used in the case where the combined lamp and shade carrier is adapted for use with electric light.

In order that my invention will be more readily understood and carried into practice, reference is hereby made to the accompanying drawings in which I have illustrated a complete device of the above mentioned type designed for the accommodation of depending electric light globes.

40 In these drawings, Figure 1 is an elevational view of a combined lamp and shade holder constructed in accordance with my invention.

Fig. 2 is a sectional view of Fig. 1 with the lamp shade in position.

Fig. 3 is a plan view of Fig. 1 with the binding nut removed for clearness.

Fig. 4 is an underside view of Fig. 1 with the lamp removed.

50 Fig. 5 is a sectional view showing gripping members in position to receive the lamp shade.

Fig. 6 is an elevational view of the porcelain insulator.

55 Fig. 7 is a plan view of Fig. 6, and Fig. 8 is a sectional view of a slightly

modified form of combined lamp and shade holder.

In these drawings wherein like numerals indicate like parts wherever occurring, the numeral 1 designates the socket shell which is of hollow form and is constructed with a projection and downwardly curved middle portion 2 in which are provided four or more holes or slots 3 through which slide 65 suitably curved fingers 4 which constitute gripping jaws for the lamp shade 5. These fingers are connected at their top ends by means of a spring wire ring 6 which passes through a circular tube 7, which is divided 70 into four pieces as indicated in Fig. 3, each piece being soldered or otherwise fixed to the top of one of the curved fingers 4. The lower ends 8 of these fingers which are preferably made of square section are bent at 75 right angles, all in the same direction, to form a ring-like support for the lamp shade which is gripped between the lower ends 8 of the curved fingers and the lower edge of the downwardly curved middle portion 2 80 of the socket shell 1.

The lower portion 9 of the socket shell 1 is of cylindrical form and is provided with the usual bayonet slot 10 for holding the base of the electric lamp bulb in position. 85

For supporting the porcelain insulating member 11 which carries the spring contact buffers 12, I provide at the top of the socket shell 1, projections 13, adapted to engage with slots 14 in the sides of the insulating member 11 near the upper end. The said top part of the socket shell is externally threaded and has two or more saw cuts 15 made in the sides, while the hollow binding nut 16 when screwed in position effectively locks 95 the insulating member 11 in place.

The porcelain member 11 I preferably form of the shape shown in Fig. 6, with two curved slots or cavities 17 extending from the top of the member to the upper part of the base. Resting on the base within the slots 17 are arranged the binding posts or terminals 18 to which are attached the sockets for the spring contact buffers 12. The flexible wire leads to the binding posts or 105 terminals 18, are conveniently housed in the cavities 17 as will be readily understood by reference to Figs. 6 and 7.

To affix, or to detach the lamp shade, the four or more curved fingers 4 are pulled or 110 pushed up until the ends 8 lie in the annular recess 19, formed underneath the curved

middle portion of the socket shell 1, so allowing the upper rim of the lamp shade to be readily withdrawn or inserted in position. When again released the four or more curved fingers 4 return to the gripping position, and the spring ring which connects the upper ends lie evenly and neatly along the top surface of the curved middle portion of the socket shell as depicted in Figs. 10 1 and 2.

Referring to Fig. 8 which shows a slightly modified form of my invention, the socket shell 1 is provided with a flange 1^a the underside of which acts as a stop for the top edge of the lamp shade 5 when the latter is in position. In this case each curved finger 4' is shaped to form the segment of a ring having knobs 4^a at the upper ends to prevent the said fingers from falling through the slots 3, and also to act as weights to further urge the fingers to their operative positions, so as to freely hold the lamp shade in its suspended position.

In the modified form of holder the means for securing the porcelain member 20 consists of an inset spring detent 21 adapted to engage in the slot 22 formed in the socket shell 1, the said detent preventing the porce-

lain member from falling out or from turning.

It will be appreciated that by my invention I have provided a convenient and simple combined lamp and shade holder which shall be inexpensive of construction and efficient in use.

What I claim and desire to secure by Letters Patent is:—

In a lamp shade holder of the character described, the combination of a socket shell with a slotted inverted cup, having an annular recess underneath of its curved middle portion, a ring slidably mounted on said socket shell, curved fingers secured with their upper ends to said ring and extending down through the slots of said cup, said fingers having a square cross-section at their lower ends for supporting a shade from the inside thereof and being adapted to be moved upward with said ring for releasing said shade, substantially as described.

In testimony whereof I affix my signature in presence of two witnesses.

THOMAS SHEPHERD.

Witnesses:

ERNALD S. MOSELEY,
MARION E. CLOUD.
